UNITED STATES PATENT OFFICE.

MAX AFTERGUT, OF BERLIN-TEMPELHOF, GERMANY.

PISTON PUMP AND SPRAYER BOTTLE.

Application filed May 12, 1924. Serial No. 712,811.

To all whom it may concern:

Be it known that I, MAX AFTERGUT, a citizen of the German Republic, residing at Berlin-Tempelhof, Germany, have invented 5 certain new and useful Improvements in Piston Pumps and Sprayer Bottles (for which I have filed patent application in Germany, May 14th, 1923, and February 25th, 1924), of which the following is a 10 specification.

The well known devices for atomizing or spraying liquids, which are mounted in the neck or opening of vessels or containers, have the drawbacks that they are subject 15 to frequent disturbances in working and that they constitute a bulky additional apparatus. According to the present invention the drawbacks in question of well known atomizing devices for liquid containers are avoided by using, for the purpose of emptying the container, a piston pump which, as regards its outer appearance and also its compactness, corresponds 20 to a simple closing device for the container. 25 The pump is so designed according to the invention that the pump piston can be connected to the neck whilst the pump cylinder or barrel which, is closed by a cover, forms a handle which is vertically adjustable 30 relatively to the container so that by periodically raising and lowering it, the liquid is pumped over the piston through a pipe or tube projecting into the said liquid.

35 The shape of the pump according to which both the piston and the cylinder are above the container and surround its neck, results in the possibility of giving the pump barrel a relatively large diameter so that 40 a relatively large volume of liquid can be pumped with a short stroke.

The pump can be mounted on a narrow neck of a vessel such as an ordinary scent bottle.

45 A construction of the improved pump and atomizing device is illustrated by way of example in the accompanying drawing in which—

Figure 1 shows it in axial section, and 50 Figure 2 shows a modification of the same, also in axial section.

In Figure 1, 1 is the upper part of a liquid container. The neck 2 of the same is screw-threaded and on the said screw-thread is screwed the piston 3 of the pump. 55 The piston has a cup-leather 4 which forms

a fluid tight joint against the wall of the barrel 5. 6 is a cover which closes the cylinder space situated above the cup-leather 4.

On the piston body 3 is mounted a tube 7, 8 which projects into the liquid in the container 1. 9 is a check valve for closing the narrower tube section 8. On the cover 6 of the cylinder is a rod 10 which carries 60 a stop 11 for limiting the stroke of the barrel 5 relatively to the piston 3, so that when the cylinder 5 is raised, it strikes the reduced portion or throat 12 at the upper end of the tube section 7. 13 is a transverse bore in the cylinder cover 6 which leads to 65 an atomizing or spraying nozzle 14 which can be of any desired, or known construction. 15 is a ball movable in the bore 13 and forming a check valve for closing the 70 connection of the bore 13 with the interior of the cylinder 5.

The working of the pump is as follows: assuming that the container 1 is filled with liquid and the cylinder 5 is in its lowest 75 position. If the cylinder 5 is raised, the liquid, owing to the reduced pressure produced in the cylinder space, will be drawn through the tube 7, 8 and pass into the cylinder space. During this time ball 15 runs backwards in the bore 13 and closes 80 its connection with the interior of the cylinder and prevents admission of air into the cylinder. During the subsequent depression of the cylinder 5, during which the check 85 valve 9 closes, the liquid contained in the cylinder will be expelled through the bore 13 and the atomizing nozzle 14, and atomized.

It will be seen from the foregoing that the invention can be adapted to bottles of 90 any desired size, even small pocket bottles without requiring any more space than a bottle with an ordinary closing device. This result is obtained by securing the piston to 95 the neck of the bottle whilst the cylinder is arranged over the bottle neck. This great advantage of the new construction can be retained even if the pump tube 7, 8 is secured to the cylinder cover instead of to the piston and participates in the movement 100 of the cylinder. In such a case it is merely necessary to make it possible for the air to pass from the cylinder, during the depression of the latter, into the bottle space above the liquid in order to ensure that the pressure of the said air will expel the liquid 105 through the pump tube.

This construction is shown in Figure 2. The cup-leather 16 is mounted in this case on a stopper 17 inserted into the bottle neck. The cylinder casing is denoted by 18 and the cylinder cover by 19. On the cylinder cover is mounted the pump tube 20, the upper end of which adjoins a transverse bore 21 in the cylinder cover 19. When the cover 19 is depressed, a rubber plate or washer 22 mounted on the tube 20 is lifted off from the bottom face of the stopper 17, so that air from the cylinder can pass by the pump tube 20 into the vessel above the level of the liquid, and the liquid can escape through the pump tube and the transverse bore 21. The cylinder cover is always held in this case in the upper position by means of a helical spring 23.

What I claim is:—

- 20 1. A piston pump for emptying liquid containers comprising a piston member adapted to be firmly connected with the mouth piece of the container and a cylinder open at one end and closed at the other 25 slidably mounted on said piston member and constituting the operating handle of the pump, the cylinder provided with an exit at its closed end, one of said pump elements provided with a tubular member forming a passage from below the piston member to above same.
2. A piston pump for emptying liquid containers comprising a piston member adapted to be firmly connected with the mouth piece of the container and a cylinder open at one end and closed at the other 30 slidably mounted on said piston member and constituting the operating handle of the pump, the cylinder provided with an exit 35 at its closed end, the piston member carry-

ing on its side opposite the cylinder cover a rising pipe for the liquid to be pumped, said pipe opening into the cylinder space and being provided with a check valve.

3. A piston pump for emptying liquid containers comprising a piston member 45 adapted to be firmly connected with the mouth piece of the container and a cylinder open at one end and closed at the other 50 slidably mounted on said piston member and constituting the operating handle of the pump, an exit from inside to outside of said cylinder at its closed end, said exit terminating in a spraying nozzle, the piston member 55 carrying on its side opposite the cylinder cover a rising pipe for the liquid to be pumped, said pipe opening into the cylinder space and being provided with a check valve.

4. A sprayer bottle comprising a bottle 60 having a neck piece, a cap mounted on said neck piece, said cap carrying a tube projecting into the bottle and provided with a check valve, the tube opening above said cap, the cap forming a piston member, a cylinder 65 slidably mounted on said piston member and forming the operating handle of a pump, means being provided to limit the operating stroke of said cylinder and handle, a conduit from inside to outside of said cylinder at the end of the cylinder remote from the end mounted on said piston member and a sprayer nozzle mounted in the mouth of said conduit.

In testimony whereof, I affix my signature 75 in the presence of two subscribing witnesses.

MAX AFTERGUT.
